US0D1027462S

(12) **United States Design Patent** (10) Patent No.: **US D1,027,462 S**
(45) Date of Patent: ** May 21, 2024

(54) **FRAME FOR ADVERTISEMENT DISPLAY**

(71) Applicant: **DAKA HOLDING uvoz-izvoz DOOEL**, Skopje (MK)

(72) Inventor: **Dimche Popovski**, Bitola (MK)

(**) Term: **15 Years**

(21) Appl. No.: **35/517,260**

(22) Filed: **May 4, 2023**

(80) **Hague Agreement Data**

Int. Filing Date: **May 4, 2023**

Int. Reg. No.: **DM/228902**

Int. Reg. Date: **May 4, 2023**

Int. Reg. Pub. Date: **May 19, 2023**

(51) **LOC (14) Cl.** 20-03

(52) **U.S. Cl.**

USPC **D20/42**; D19/113; D6/300

(58) **Field of Classification Search**

USPC D6/300–314; D20/43, 44, 99; D19/113

CPC G09F 1/12

See application file for complete search history.
